C. A. B. HALVORSON, JR

TRAFFIC SIGNAL

Filed Sept. 18, 1924

Inventor:
Cromwell A.B. Halvorson Jr.
by *Wm. and Wm. S. Lantz*
His Attorney.

UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

DESIGN FOR A TRAFFIC SIGNAL.

Application filed September 18, 1924. Serial No. 10,817. Term of patent 14 years.

To all whom it may concern:

Be it known that I, CROMWELL A. B. HALVORSON, Jr., a citizen of the United States, residing at Lynn, in the county of Essex and State of Massachusetts, have invented a new, original, and ornamental Design for Traffic Signals, of which the following is a specification, reference being had to the accompanying drawing, forming a part thereof.

The accompanying drawing is a perspective view of my new design.

I claim:

The ornamental design for a traffic signal as shown.

In witness whereof, I have hereunto set my hand this thirteenth day of September, 1924.

CROMWELL A. B. HALVORSON, JR.
